UNITED STATES PATENT OFFICE.

JOHN FENSON, OF TORONTO, ONTARIO, CANADA.

HOIST.

SPECIFICATION forming part of Letters Patent No. 239,157, dated March 22, 1881.

Application filed February 11, 1881. (No model.)

To all whom it may concern:

Be it known that I, JOHN FENSON, a subject of the Queen of Great Britain, residing at Toronto, in the county of York, in the Province of Ontario, Canada, have invented certain new and useful Improvements in Hoists for Store-Houses and other Buildings, of which the following is a specification.

My invention has relation to a hoisting apparatus, in which a water-engine or other motor is employed as an auxiliary to a counterbalance-weight, for the purpose of elevating the car when heavily loaded, and as the means whereby the car can be lowered when empty; and has for its object the arrangement of the counterbalance-weight and auxiliary motor, by which a motor of one-half the power may be employed to perform a given service.

In the operation of a hoist embodying my improvements I propose to make the counterbalance sufficiently heavy to elevate the majority of loads carried up by the hoist; but when the load is increased beyond the lifting-power of the counterbalance-weight then the water-engine or other motor is employed as an auxiliary to the weight for the purpose of lifting the extra amount of the load only. In connection with the engine and counterbalance-weight I use a brake which is controlled by a check-rope, and which is arranged to govern the speed of movement of the car. The operation of the motor is also controlled from the check-rope or its equivalent, which extends from the bottom to the top of building in the hoist-well, and is always at the command of the person on the hoist. A hoist thus designed can be operated with the utmost economy, as it would be found seldom necessary, except when a large consignment of goods was being taken into or out of store, to use the water-engine or other motor if judgment is used in the handling of the upward and downward bound goods.

In order that my invention may be thoroughly understood by those familiar with the construction of hoists, I submit drawings which exhibit the application of my invention to an ordinary hand-hoist.

Figure 1 is a perspective view of an ordinary hoist operated by a hand-rope, C, and in which the counter-balance I is made sufficiently

heavy to counterbalance the weight of the car J carrying an average load. So far my hoist is constructed in all respects in the usual manner, the auxiliary power which I apply for the purpose of elevating the hoist when the load upon the car J makes the weight greater than the counterbalance-weight I will elevate, or when the weight upon the car J is not sufficient to overcome the weight of the counterbalance, when it is desired to cause the car J to descend it is so arranged that it can be brought into action when necessity arises for its use.

In addition to the perspective view of the hoist shown in Fig. 1, I submit details of preferred mechanism for applying the auxiliary power, Fig. 2 being a plan of the friction mechanism for grasping the rope, Fig. 3 an end view thereof, Fig. 4 a side view, and Fig. 5 a plan showing the application of the brake to the rope-wheel K.

In the drawings, A represents a spindle carried in bearings rigidly connected to the frame a. This frame may be of any design and bolted to the floor in the position shown. The spindle A is made to revolve by the belt b, either constantly or intermittently, according to the description of motor employed, as will be hereinafter explained.

B are grooved pulleys, keyed or otherwise fastened to the spindle A in such relative position to the rope C that the said rope can be pressed into the grooves of the pulleys B, as hereinafter explained.

D is a spur-wheel, keyed or otherwise fastened to the spindle A, and meshing with the spur-wheel E, keyed or otherwise fastened to the spindle F. This spindle is carried in bearings attached to the plate e, which is centrally pivoted to the frame a on the pin f, as is clearly shown in details of this part of my mechanism.

G are grooved pulleys, keyed or otherwise fastened to the spindle F, and situated similarly to the pulleys B, opposite to the hand-rope C, as indicated in Fig. 1.

On the bottom of the frame a, I cast or otherwise attach a lug, g, which constitutes a bearing for the crank h. The end of this crank is connected by a rod, i, to a lug on the bottom of the plate e. The pivot upon which the crank h is carried has attached to it an arm,

K, the movement of which rocks the crank backward or forward as the said arm is moved up or down, as the case may be. As the plate e is pivoted upon the frame a, and is connected 5 to the crank h, as described, it follows that the plate e is moved upon its pivot in proportion to the motion of the arm K; and owing to the location of the grooved pulleys B and G the rope C is grasped by these pulleys either 10 on one side of the hoist or the other, according to the movement of the lever K, the distance between the grooved pulleys B and G being such that when the spindle F is parallel with the spindle A the rope C passes freely between 15 them, and can thus be used as an ordinary hand-hoist.

In order to operate the lever K it is suitably connected, as shown in the drawings or otherwise, to the check-rope H. The check-rope 20 which I usually employ is an endless one, passing over a pulley, L, at the top of the hoist and over a similar pulley, M, at or near the base of the hoist. It will thus be seen that the operator on the car at any point in its elevation 25 can, by grasping the check-rope H, apply the motor to the rope C so as to raise or lower the car as he may at the time desire. This use for the check-rope H would in itself not be singular if it were applied to a power-30 hoist; but in order to carry out the principle of my invention the mechanism I employ is arranged to grasp the hand-rope C so as to raise or lower the car, and the pulley L, over which the rope H passes, as will be seen in 35 Fig. 5, is provided with a spindle having a crank, l, which is connected to the brake m by the rod n. In ordinary cases, where the car J is not called upon to carry more than an average load, the weight I is, as I have before 40 said, made sufficiently heavy to raise the car so loaded. In this case the operator draws upon the rope H only far enough to raise the brake m clear of the rope-wheel K; but should he find the weight I insufficient he draws upon 45 the rope H a little further, which action causes the groove-pulleys B and G to grasp the rope C, and thus bring into action the auxiliary motor.

When a gas-engine or other motor which it 50 is necessary to keep constantly in motion is employed the spindles A and F are always revolving. The pulleys B and G are therefore ever ready to be instantly brought into action for assisting in the operation of the hoist, as 55 described.

When a water-engine or other motor which need not be kept constantly going is employed I connect its valve or starting-lever, by any suitable mechanical means, to the pulley M. 60 For the purpose of illustrating this application I show a spindle, O, which is supposed to represent the valve-spindle of the motor placed below the floor. The end of this spindle is provided with a link, as shown, into 65 which a pin on the face of the pulley M extends. When the pulley M is thus connected, or by any other suitable mechanical means, to

the valve or starting-lever of the motor referred to, the movement of the check-rope H first removes the brake m from the rope-wheel K, and then starts the motor, the pulleys B and G being caused to grasp the rope simultaneously with the last action. 70

In order to instantly apply the brake, and at the same time disconnect the auxiliary motor from the rope C, the ordinary equalizing-rope may be used. The application of this to the check-rope H is shown in Fig. 6. 75

In a former part of this specification I mention that when a motor is employed which requires to be constantly in motion the spindles A and F will always be revolving. While I think that this will probably be the preferable arrangement, it will, of course, be understood that a belt-shifter or friction-brake might 80 be operated in the same way as the intermittent motor is started. I also wish to remark that while I prefer the check-rope, a rod or chain might be made to answer its purpose. 85

Having described the construction and operation of the mechanism by which I accomplish the object of my invention, it seems almost superfluous to remark that, owing to its application, great economy is secured, not only in the original cost, but also in the daily expense of operating the hoist. For the purpose of illustrating this statement, we will assume that a merchant requires a hoist capable of elevating one ton. In purchasing a hoist he would, in ordinary cases, be compelled to purchase a motor capable of exerting a power equal to this weight; whereas by the application of my invention a motor of one-half the power would accomplish the purpose, the motor being so arranged that it can be applied 100 to the hand-rope for the purpose of either elevating or lowering the car, the auxiliary motor being thus brought into requisition to raise the car when its load to be raised is greater than the counterbalance-weight, or to assist 105 in lowering the car when its load to be carried down is less than sufficient to overbalance the effect of the counter-weight. 110

What I claim as my invention is—

1. In hoists, the car provided with a counterbalance-weight adapted to lift the car and an average load, in combination with the check-rope or its equivalent connected to the brake and to operating machinery in such a manner that by the movement of the check-rope a given distance the brake is thrown off, while the continuation of the said movement throws into gear with the hoist auxiliary operating machinery, substantially as specified. 115

2. In combination with a hoist provided with an ordinary hand-rope, and in which the counter-balance to the car is adapted to lift the car and an average load, an auxiliary motor arranged so that it can be thrown into gear with the hand-rope by the check-rope after the 120 said check-rope has first thrown off the brake. 125

3. In combination with a hoist provided with an ordinary hand-rope, and in which the counterbalance to the car is adapted to lift the car

and an average load, friction mechanism operated by the check-rope and arranged to gripe the hand-rope simultaneously with the starting of an auxiliary motor operated by the said check-rope, for the purpose of imparting motion to the friction mechanism subsequent to the releasing of the brake, also operated by the check-rope referred to.

4. The revolving spindle A, held in stationary bearings and having keyed or otherwise fastened to it the grooved pulleys B, situated opposite to the hand-rope C, a spur-wheel, D, fastened to the spindle A and meshing with the spur-wheel E, which is fastened to the pivoted spindle F, the grooved pulleys G, secured to the spindle F, and situated in a position corresponding with the pulleys B, in combination with mechanism connected to the check-rope H, by the movement of which the spindle F is

adjusted upon its pivot so as to cause the 20 grooved pulleys B and E to grasp the rope C on whichever side of the hoist it may be necessary to apply power to the said rope, for the purpose of raising or lowering the car, as the case may be.

5. In combination with a hoist provided with an ordinary hand-rope, and in which the counter-balance to the car is adapted to lift the car and an average load, an auxiliary motor so arranged, in connection with the hand-ropes, 30 that it can be applied thereto for the purpose of assisting in either elevating or lowering its load.

JOHN FENSOM.
